UNITED STATES PATENT OFFICE.

NATHAN J. GOODMAN, OF ST. LOUIS, MISSOURI, ASSIGNOR TO SIMPLEX SELF HOLDING CARTON CO., OF ST. LOUIS, MISSOURI, A CORPORATION OF MISSOURI.

CARTON OR HOLDER FOR LAUNDRY ARTICLES.

942,201.

Specification of Letters Patent.

Patented Dec. 7, 1909.

Application filed March 3, 1909. Serial No. 481,043.

To all whom it may concern:

Be it known that I, NATHAN J. GOODMAN, a citizen of the United States, and resident of St. Louis, Missouri, have invented certain new and useful Improvements in Cartons or Holders for Laundry Articles, of which the following is a specification containing a full, clear, and exact description, reference being had to the accompanying drawings, forming a part hereof.

My invention relates to a carton or holder particularly adapted for holding laundry shirts, shirt waists, vests, and the like, the object of my invention being to provide a simple, inexpensive carton or holder which may be readily folded for use, and which maintains the contained article in a neat, clean and convenient manner without the use of pins, bands, or like fastening devices.

To the above purposes, my invention consists in certain novel features of construction and arrangement of parts which will be hereinafter more fully set forth, pointed out in the claims, and illustrated in the accompanying drawings, in which:

Figure 1 is a perspective view of a carton of my improved construction, the same being in an open position and ready to receive a shirt, or the like; Fig. 2 is an end elevation of the carton, the same being partially folded; Fig. 3 is a perspective view of the carton in a folded condition and containing a laundry article; Fig. 4 is an enlarged section taken on the line 4-4 of Fig. 3; and Fig. 5 is an enlarged detail section taken on the line 5-5 of Fig. 3.

Referring by numerals to the accompanying drawings: 1 designates the base of the carton, which is preferably constructed of comparatively stiff card-board, or analogous material, rectangular in form and of such size as to readily accommodate a shirt or like article of wearing apparel when the same is folded after being laundry. Formed in the ends of the base 1 are transversely disposed slots 2.

The wrapper or inclosing member of the carton comprises a rectangular section 3 of thin transparent paper, or analogous material, the length of which is approximately three times the width of the base 1, and one edge of the base 1 is attached to the section 3 by a suitable adhesive in such a manner as that said base 1 occupies a po-

sition on the central portion of the section 3, and the end portions of the section 3 are adapted to fold over onto the back of the base 1.

Secured to the ends of the section 3 are narrow strips 4, of card-board or analogous material, and the ends of one of these strips project beyond the sides of the section 3 to form tongues 5.

The cartons or holders thus constructed are delivered to the packer in a flat open condition, as seen in Fig. 1, and the shirt or like article, after being properly folded, is positioned between the base 1 and the corresponding central portion of the wrapper section 3 with the bosom of the shirt immediately adjacent said wrapper section, which arrangement permits the front or bosom of the shirt to be seen through the transparent wrapper section when the carton is properly folded.

The ends of the section 3 carrying the strips 4 are now brought together above the central portion of the back 1, as shown in Fig. 2, and said end sections are now rotated to wind the end portions of the wrapper together, thus taking up the extra material in the end portions of said wrapper, and when the strips 4 are brought into a position immediately against the base 1, the tongues 5 are inserted through the slots 2 and said tongues are bent rearward beneath the base 1, thus securely fastening the folded ends of the wrapper section 3. Thus the shirt or inclosed article is held in a neat and convenient manner so that it cannot become soiled as a result of handling during delivery, and as the wrapper section is formed of thin transparent material the bosom or front of the shirt can be readily inspected by the customer, and the marks which are usually placed on the collar band of the shirt can be readily observed by the distributor of the laundry articles.

Cartons of my improved construction are particularly applicable for inclosing laundry articles, although they may be advantageously used for holding any articles of wearing apparel and the like which are displayed for sale and which are to be delivered to a customer in a neat and clean condition.

I claim:

1. A carton of the class described, comprising a base of comparatively stiff mate-

rial, a wrapper section composed of a single sheet of thin, transparent flexible material secured to one edge of said base, the said base section being disposed approximately centrally of the wrapper section, and strips of stiff material secured to the terminal portions of the wrapper section.

2. A carton of the class described, comprising a base of comparatively stiff flexible material, a wrapper section composed of a single sheet of thin, transparent material secured to one edge of said base so that about equal portions of the wrapper section project beyond the edges of the base, a strip of stiff material secured to one side of the wrapper section, and a strip of stiff but flexible material secured to the opposite side of the wrapper section, the ends of which latter strip project beyond the wrapper section to form tongues for engaging the base of the carton when it is folded.

3. A carton of the class described, composed of a wrapper section of a single sheet of thin, transparent material, a base provided with slots and of comparatively heavy material, one edge of which is secured to said wrapper section so that said base occupies a position comparatively centrally of said wrapper section, a strip of stiff material secured to one side of said wrapper section, a strip of stiff but flexible material secured to the opposite side of said wrapper section, the ends of which strip project beyond the wrapper section for engaging the slots formed in the base section when folded.

4. A carton of the class described, composed of a wrapper section of a single sheet of thin, transparent material, a base pro-

vided with curved slots and of comparatively heavy material, one edge of which is secured to said wrapper section so that said base occupies a position comparatively centrally of said wrapper section, a strip of stiff material secured to one side of said wrapper section, a strip of stiff but flexible material secured to the opposite side of said wrapper section, the ends of which strip project beyond the wrapper section for engaging the curved slots formed in the base section when folded.

5. A carton of the class described, comprising a wrapper section of a single sheet of thin, transparent material, a base section provided with curved slots and of comparatively heavy material, one edge of said base being secured to said wrapper section so that said base occupies a comparatively central position on said wrapper section, the length of the base being the same as the width of the central portion of the wrapper section, and the width of the wrapper section beyond the base being narrower than the length of the base section, a strip of stiff but flexible material secured to one side of the wrapper section, its ends projecting beyond the wrapper section so as to form tongues to engage with the slots in the base section when the carton is folded.

In testimony whereof, I have signed my name to this specification, in presence of two subscribing witnesses.

NATHAN J. GOODMAN.
